SEPARATOR

James Fletcher, Akron, Ohio, assignor to The Babcock & Wilcox Company, Newark, N. J., a corporation of New Jersey

Application December 4, 1937, Serial No. 178,182

9 Claims. (Cl. 122—491)

The present invention relates in general to the construction and arrangement of the internal parts of a steam generating unit steam and water drum, and more particularly of internal parts 5 for minimizing the moisture content of the steam leaving the drum.

The main object of the invention is the provision of an improved construction and arrangement of the internal parts of a steam and water drum adapted for use in a high capacity 10 high pressure steam generating unit for minimizing the moisture carryover from the drum. A more specific object is the provision of a steam and water drum internal construction for minimizing the disturbance of the drum water level 15 due to the entry into the drum of the discharge from the steam generating tubes.

The various features of novelty which characterize my invention are pointed out with particularity in the claims annexed to and forming a part of this specification. For a better understanding of the invention, its operating advantages and specific objects attained by its use, reference should be had to the accompanying 20 drawings and descriptive matter in which I have illustrated and described a preferred embodiment of my invention.

Of the drawings:

Fig. 1 is a sectional elevation of a high pressure 30 high capacity steam generating unit of one type to which my invention is particularly applicable;

Fig. 2 is a transverse section taken on the line 2—2 of Fig. 1;

Fig. 3 is an enlarged sectional view of the steam and water drum shown in Fig. 1 taken on the line 3—3 of Fig. 4;

Fig. 4 is a partial longitudinal section taken on the line 4—4 of Fig. 3; and

Fig. 5 is a horizontal section taken on the line 5—5 of Fig. 4.

In Figs. 1 and 2 is illustrated a high pressure high capacity steam generating unit comprising a fluid cooled two-stage pulverized fuel burning furnace 10 arranged below a steeply inclined bank of steam generating tubes 11 having their upper and lower ends connected to uptake and downtime headers 12 and 13 respectively. The uptake headers 12 are connected by circulator 45 tubes 14 to a horizontally arranged steam and water drum 15 extending transversely of the unit a substantial distance above the downtime headers 13. Downcomer tubes 16 extend between the bottom of the drum 15 and the downtime headers 13.

In the space defined by the tube bank 11 and the tubes 14 and 16 is arranged the economizer and superheater sections of the unit. This space is divided longitudinally of the tube bank by a 50 partition 17 to form a pair of parallel upflow

damper controlled gas passes 18 and 19 above the tube bank. The economizer surface is formed by a downflow bank of return bend water tubes 20 extending across both gas passes and a plurality of upflow banks of return bend tubes 21 in the gas pass 18, the uppermost tube legs 21 being connected to the drum 15. The superheating surface is formed by vertically spaced banks of return bend tubes 22 in the gas pass 19 with the uppermost tube legs 22 connected to the 10 steam space of the drum 15 by steam outlet tubes 23. The two-stage furnace 10 has all of its walls and its dividing partition cooled by water tubes, which in turn are connected to the drum 15 by suitable connections, including groups of riser 15 tubes 24 opening into the water space of the drum 15 adjacent the ends thereof, as shown in Fig. 4, and riser tubes 25 opening into the steam space of the drum along its length. The drum 15 will thus receive all of the steam generated 20 in the unit through the tubes 14, 24, and 25, and is advantageously provided with internal parts for insuring a minimum moisture content in the steam passing to the outlet tubes 23 and a minimum steam content in the water entering the 25 downcomer tubes 16.

The internal construction of the steam and water drum 15 is illustrated in Figs. 3 to 5. The normal water level is at or slightly below the drum horizontal center line, as indicated by the 30 broken line 26 in Figs. 3 and 4. As shown, the circulator tubes 14 have a radial connection with the drum along one side thereof in two rows at or slightly above the horizontal center line of the drum. In order to minimize disturbance of the 35 water surface in the drum due to impingement thereon of the high velocity streams of steam and water discharged by the tubes 14 and to effect an initial separation of the steam and water, each pair of vertically adjacent circulator 40 tubes 14 are arranged to discharge into a corresponding splash compartment or box 30.

The splash boxes 30 are longitudinally spaced along one side of the drum, as shown in Fig. 4, and each is formed by a vertically extending impact plate 31 having a vertical lower portion 31^a extending from the drum horizontal center line to the drum wall, and an upper inclined portion 31^b extending towards but terminating short of the drum wall at a level slightly above the 50 discharge ends of the upper row of tubes 14 to provide an opening 32 from the box along the drum wall. The sides of the splash boxes are formed by vertical side plates 33 extending between and secured to the plate 31 and drum wall. 55 The side plates 33 have their lower edges 34 submerged and terminating above the corresponding portion of the drum wall. The upper end of each plate 33 is cut away to form relatively large 60

openings 35 at the opposite sides of each box above the normal water level.

With this arrangement the steam and water discharged from each pair of circulator tubes 14 is initially directed against the inclined plate portion 31^b and deflected downwardly towards the portion of the drum water space within the corresponding splash box. A relatively rough primary separation of the steam and water is effected in the splash box with the separated water collecting in the water space of the box and eventually flowing therefrom below the opposite side plates, while the wet steam passes outwardly through the top opening 32 and side openings 35. The velocity of the entering streams of steam and water is thus substantially reduced and the disturbance of the water surface mainly confined to the water surface in the splash box. A stepped series of normally submerged horizontally arranged plates 37 extend between the side plates 33 with their edge portions slightly overlapping to obstruct the downward flow of steam bubbles through the water space and thereby contribute to the maintenance of a water supply of the desired density to the downcomer tubes 16. The highest plate 37 is arranged along the plate 31, and the lowest along the drum wall.

The streams of steam and water discharged from each group of water wall riser tubes 24 are broken up and dispersed by a pair of horizontally extending perforated plates 38 arranged in the drum water space in the path of the discharge from the tubes 24. The plates 38 are held in the desired position by spacers 39 and supporting members 40 extending across the drum.

The water wall riser tubes 25 open into the drum 15 above and intermediate the pairs of circulator tubes 14 and the corresponding splash boxes, each tube 25 being provided with a pipe extension 41 which extends across the steam space of the drum to a point adjacent the opposite drum wall portion. The riser tube extensions 41 project through and are supported by a vertical plate or partition structure 42 extending substantially the full length of the drum and having its upper and lower ends terminating short of the corresponding portions of the drum wall. The plates 42 are carried by longitudinally spaced vertical angle bars 43 fitting against and welded to the drum wall. The plate structure 42 forms an elongated space 45 along the drum side opposite the splash boxes, into which space the tubes 25 will thus discharge. The discharge ends of the extensions 41 may be cut off at an angle of 45°, as indicated in Fig. 3. The wet steam leaves the space 45 over the top of the plates 42 or through the ends of the space, while the separated water may flow below the lower end of the plate 42 into the central water space.

The steam and water drum 15 is also desirably provided with apparatus for washing the steam entering the central portion of the drum. For this purpose the economizer tubes 21 extend through the lower portion of the drum and are connected by nipples 50 extending through the plate sections 31^a to a feed manifold 51 extending longitudinally of the water space of the drum. The feed manifold is connected at longitudinally spaced points to pipes 52 leading upwardly through the drum steam space and discharging between a pair of inverted V-shaped spatter pans 54 which direct the wash water towards opposite sides of the drum.

A twin type corrugated plate separator is symmetrically arranged longitudinally of the upper

portion of the drum and comprises a pair of oppositely inclined separator sections 60 at opposite sides of the connections of the steam outlet tubes 23. Each of the sections 60 is formed by a multiplicity of uniformly corrugated parallel plates 5 arranged to form narrow sinuous channels therebetween. The corrugated plates extend from the drum wall to a common bottom plate 61 which is carried by hook bolts 62 supported by brackets 63 welded to the drum wall. The bottom plate 61 closes the lower end of the plate channels over a major portion of their extent and has its central portion shaped to form a common central moisture collecting chamber 64. Drain pipes 65 having their lower ends extending into the water space are connected to the chamber 64. The flow areas through the separator sections are proportioned to effect a low velocity steam flow therethrough, which with the described separator and bottom plate arrangement will permit a major portion of the separated moisture to flow down the bottom plates 61 oppositely to the steam flow. A V-shaped perforated plate 66 is arranged at the inner side of the sections 60 forming a common steam collecting space 67 below the outlet tubes 23. Longitudinally extending curves deflecting baffles 68 extend along the opposite sides of the twin type separator to deflect the steam discharged over the upper end of the plates 31 and 42 downwardly away from the twin type separator and into the path of the washing sprays.

With the described arrangement and construction of the drum internal parts all of the steam generated will be subjected to a primary moisture separating action in portions of the drum substantially separate from the main body of water, and the disturbance of the water surface mainly confined to these sections. The use of a large number of small splash boxes of the construction described not only provides a more effective treatment of the entering steam and water, but also causes the steam to enter the main portion of the drum throughout its length. Relatively quiescent water conditions will be thus maintained in the main portion of the drum to which the downcomer tubes 16 are connected. The described relative arrangement of the washing sprays, twin type separator, and deflecting baffles insures effective washing of the steam and separation of the moisture remaining in the washed steam before leaving the drum. The drum internal parts are relatively easy to install and render the downcomer tube connections accessible for inspection and cleaning.

While in accordance with the provisions of the statutes I have illustrated and described herein the best forms of the invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. In combination, a horizontally elongated steam and water drum having a water space and a steam space, a steam outlet from said steam space, steam generating tube connections opening into and along the length of said drum, and means cooperating with the drum wall to form a series of separate compartments in and longitudinally spaced apart along one side of said drum, each enclosing the discharge ends of cor-

responding tube connections and having a submerged opening therein to said water space and a steam exit opening to said steam space in the upper part of a vertical side thereof extending transversely of said drum.

5. In combination, a horizontally elongated steam and water drum having a water space and a steam space, a steam outlet from said steam space, steam generating tube connections opening into and along one side of said drum adjacent the normal water level therein, and means cooperating with the drum wall to form a series of separate compartments of rectangular cross-section in and longitudinally spaced apart along one side of said drum, each enclosing the discharge ends of a small group of said tube connections and having a submerged opening in the sides thereof to said water space and a steam exit opening in the upper part thereof to said steam space.

6. In combination, a horizontally elongated steam and water drum having a water space and a steam space, a steam outlet from said steam space, steam generating tube connections opening into and along the length of said drum, means forming a series of separate compartments in and longitudinally spaced apart along one side of said drum, each enclosing the discharge ends of a small group of said tube connections, and said means including an impact plate arranged directly in the path of discharge of said generating tubes, and a pair of side plates extending from the sides of said impact plate to said drum wall, said side plates being constructed to form a submerged opening in the sides of each compartment to said water space and a steam exit opening to said steam space.

7. In combination, a horizontally elongated steam and water drum having a water space and a steam space, a steam outlet from said steam space, steam generating tube connections opening into and along the length of said drum adjacent the normal water level therein, means forming a series of separate compartments in and longitudinally spaced apart along one side of said drum, each enclosing the discharge ends of a small group of said tube connections, said means including a partly submerged impact plate having its upper end spaced from said drum wall and extending inwardly and downwardly directly into the path of discharge of said tube connections, and a pair of side plates extending from the sides of said impact plate to said drum wall, said side plates being constructed to form submerged openings in the sides of each compartment to said water space and a steam exit opening to said steam space.

8. In combination, a horizontally elongated steam and water drum having a water space and a steam space, a steam outlet from said steam space, steam generating tube connections opening into and along the length of said drum, means forming a series of separate compartments in and longitudinally spaced along one side of said drum, each enclosing the discharge ends of a small group of said tube connections and having a submerged opening in the sides thereof to said water space and a steam exit opening to said steam space, and a plurality of submerged horizontal baffles arranged in a stepped formation across each compartment.

9. In combination, a horizontally elongated steam and water drum having a water space and a steam space, a steam outlet from said steam

space, steam generating tube connections opening into and along the length of said drum adjacent the normal water level therein, means forming a series of separate compartments in and longitudinally spaced along one side of said drum, each enclosing the discharge ends of a small group of said tube connections, said means including a partly submerged impact plate having its upper end spaced from said drum wall and extending inwardly and downwardly directly into the path of discharge of said tube connections, a pair of side plates extending from the sides of said impact plate to said drum wall, said side plates being constructed to form a submerged opening in the sides of each compartment to said water space and a steam exit opening to said steam space, and submerged horizontal baffles arranged longitudinally of said drum in a stepped formation across each compartment.

10. In combination, a horizontally elongated steam and water drum having a water space and a steam space, a steam outlet from said steam space, steam generating tube connections opening into and along the length of said drum, means forming a series of separate compartments in and longitudinally spaced along one side of said drum, each enclosing the discharge ends of a small group of said tube connections and having a submerged opening therein to said water space and a steam exit opening at its upper end to said steam space, a steam and water separator in the upper portion of said steam space, steam washing means below said separator, and a deflecting baffle on the drum wall between said compartments and said separating means arranged to deflect steam leaving said exit opening towards said steam washing means.

11. In combination, a horizontally elongated steam and water drum having a water space and a steam space, a steam outlet from said steam space, steam generating tube connections opening into and along the length of said drum, means forming a series of separate compartments in and longitudinally spaced along one side of said drum, each enclosing the discharge ends of a small group of said tube connections and having a submerged opening therein to said water space and a steam exit opening to said steam space, a vertical plate structure at the opposite side of said drum forming a longitudinal extending chamber having a steam outlet at its upper end, and steam generating tube connections extending across said drum above said compartments and opening to said chamber through said plate structure.

12. In combination, a horizontally elongated steam and water drum having a water space and a steam space, a steam outlet from said steam space, steam generating tube connections opening into and along the length of said drum, and means cooperating with the drum wall to form a series of separate compartments in and longitudinally spaced apart along one side of said drum, each enclosing the discharge ends of corresponding tube connections and having a submerged opening therein to said water space and steam exit openings to said steam space in the top and in a vertical side thereof extending transversely of said drum, and a deflecting baffle extending from the drum wall into the path of steam flow from said compartments.
